ATHLETIC GAME PADDLE

James W. Maddox, 6515 S. Laflin,
Chicago, Ill. 60636

Filed Jan. 28, 1969, Ser. No. 15,533

Term of patent 14 years

Int. Cl. D21—03

U.S. Cl. D34—5

FIG. 1 is a perspective view of an athletic game paddle showing my new design;

FIG. 2 is a rear view of the paddle;

FIG. 3 is a side view;

FIG. 4 is a top view;

FIG. 5 is a front view;

FIG. 6 is a sectional view taken along the line 6—6 of FIG. 3;

FIG. 7 is a perspective view of another embodiment of my athletic game paddle showing my new design;

FIG. 8 is a rear view of the paddle;

FIG. 9 is a side view;

FIG. 10 is a top view;

FIG. 11 is a front view; and

FIG. 12 is a sectional view taken along the line 12—12 of FIG. 9.

I claim:

The ornamental design for an athletic game paddle, substantially as shown and described.
